(57) **CLAIM**

The ornamental design for a motor, as shown and described.

DESCRIPTION

FIG. 1 is a perspective view of a preferred embodiment of the motor of the invention;

FIG. 2 is a front axial view thereof;

FIG. 3 is a rear axial view thereof;

FIG. 4 is a right side view thereof;

FIG. 5 is a left side view thereof;

FIG. 6 is a top view thereof; and,

FIG. 7 is a bottom view thereof.

The broken line showing of portions of a motor is included for the purpose of illustrating environmental structure and forms no part of the claimed design.
